UNITED STATES PATENT OFFICE.

NOYES F. PALMER, OF NEW YORK, N. Y.

HOPPER.

SPECIFICATION forming part of Letters Patent No. 758,681, dated May 3, 1904.

Application filed October 29, 1903. Serial No. 178,972. (No model.)

To all whom it may concern:

Be it known that I, NOYES F. PALMER, a citizen of the United States, residing at New York city, (Brooklyn,) county of Kings, and State of New York, have invented new and useful Improvements in Hoppers, of which the following is a specification.

This invention relates to a hopper more especially designed for molds adapted for the manufacture of artificial stones and for similar purposes.

My improved hopper can be readily manipulated and greatly facilitates the charging of the mold as well as the striking off of the green block.

In the accompanying drawings, Figure 1 is a longitudinal section, partly in elevation, of my improved hopper, showing it lowered; Fig. 2, a similar view, partly broken away, showing the parts in a different position; Fig. 3, a side view of the hopper, showing it raised with the mold in section; Fig. 4, an enlarged cross-section on line 4-4, Fig. 2; Fig. 5, an end view of the hopper; and Fig. 6, an enlarged cross-section on line 6-6, Fig. 1.

The hopper proper is composed of two inclined side plates *a* and an inclined front plate *a'*, while its back is open. Angle-irons *a²* connect the sides *a* to the front *a'* and are attached at the open back to a transverse bar *a⁵*. The angle-irons *a²* are bent outwardly and upwardly at the top, as at *a³*, to accommodate a pair of rails *b*, which are secured to the angle-irons by screws *b'* or otherwise. At their lower ends the angle-irons *a²* terminate in stepped projections *a⁴*, Fig. 3, which engage the similarly-stepped upper edge *c'* of the mold *c*. This mold has preferably hinged or movable sides, which are thus locked by the hopper against spreading or opening at the corners when the concrete is being tamped.

The rails *b* are of a length to extend beyond both sides of the hopper proper and are hinged at their lower or left-hand ends *b²*, Fig. 3, to a suitable support or frame *d*. At their upper ends the rails *b* are connected to a counterweight *e* by a rope *e'*, running over pulleys *f*. When the rails *b* are swung up, Fig. 3, they, together with the hopper, will be sustained in a vertical position by means

of the counterweight. When the rails are lowered into a horizontal position, Fig. 1, the hopper will be set squarely upon the mold, to which it will become locked by a spring-catch *g*. Thus it will be seen that the hopper may be readily fitted to the mold while the latter is to be filled and may as readily be removed while the mold is opened and the green block is removed.

Upon the rails *b* is free to slide a cut-off box *h*, guided along the rails by flanges *h'*, that engage corresponding grooves of the rails. The box *h* may travel to and fro within the hopper and when not in use may be pushed through the open back of the latter and upon the right-hand extension of the rails *b*, so as to clear the hopper, Fig. 1. The box is open at its front or inner side and is here provided with an inclined downwardly-extending knife or blade *h²*, which is adapted to strike off the green block. Thus when the box is moved toward the left the knife will cut off the block and the cut-off upper stratum will be pushed into the box.

i is a filling-box, which is also slideable on the rails *b* and is held thereto by the flanges *i'*. This box is free to be moved to and fro along the rails above the hopper and when out of use may be pushed upon the left-hand ends of the rails *b*. The rails *b* connect at their left end with a fixed track *j* of frame *d*, so that the box *i* may be readily transferred from the rails *b* upon the track *j*. The box *i* is provided with a center partition *i'* and with a double trap-bottom, the two sections *i²* of which are hinged to the box at a distance above its open lower end, as at *i³*. Thus when the trap-bottom is opened the contents of the box will be dumped into the hopper. When the trap is closed, its sections *i²* are locked in a horizontal position by suitable catches *i⁵*.

The operation of the device will be readily understood. The box *i*, standing upon the track *j*, is filled with concrete. The hopper is swung down to engage the mold and the box *i* is pushed upon and along the rails *b* until it arrives over the hopper. The trap-bottom *i²* is now opened to dump the concrete through the hopper into the mold, after which the box is

returned to the track *j* and the concrete is tamped in the mold. The cut-off box *h* is next advanced to strike off the block and gather the surplus into the box. As the rails *b*, together with the hopper and box *h*, are next swung up this surplus will be dumped into the pit ready to be shoveled into the box *i* for the next block.

It will be seen that my improved hopper can be quickly manipulated and that it provides means for readily charging the mold and returning the surplus to the dump. In this way the operation of molding the block is greatly accelerated, while cleanliness is insured and waste is avoided.

What I claim is—

1. The combination of a hopper with a cut-off box movable within the hopper, and with a cutter depending from the box, substantially as specified.
2. The combination of a hopper having an open back with a pair of rails projecting beyond the same, a cut-off box movable along the rails, and a cutter depending from the box, substantially as specified.
3. The combination of a hopper with a fill-

ing-box movable above the hopper, and with a trap-bottom in the filling-box, substantially as specified.

4. The combination of a hopper with a pair of hinged rails projecting beyond the same, fixed track adapted to connect with the said rails, and a filling-box having a trap-bottom and movable along the rails, substantially as specified.

5. The combination of a pair of rails with a hopper carried thereby, and with a cut-off box and a filling-box movable along said rails, substantially as specified.

6. The combination of a pair of rails with a hopper carried thereby and having an open back, a cut-off box having a depending cutter and a filling-box having a trap-bottom, the cut-off box and filling-box being movable along the rails, substantially as specified.

Signed by me at New York city, (Manhattan,) New York, this 28th day of October 1903.

NOYES F. PALMER.
